(57) **CLAIM**

The ornamental design for a muffler, substantially as shown and described.

DESCRIPTION

FIG. 1 is a perspective view of a muffler showing an embodiment of the new design;

FIG. 2 is a first side view of an embodiment of the muffler;

FIG. 3 is a second side view of an embodiment of the muffler;

FIG. 4 is a front view of an embodiment of the muffler;

FIG. 5 is a top view of an embodiment of the muffler; and,

FIG. 6 is a bottom view of an embodiment of the muffler.

The broken line showing of aspects of the muffler in FIG. 6 is included for the purpose of illustrating environment and forms no part of the claimed design.
